[57] ABSTRACT

A waveguide having an internal wall formed by a plurality of insulated straps of conductive material wound on edge in a helix so that the major surfaces thereof face each other, each strap being of a different cross-section or being differently disposed so as to leave a space between adjacent major surfaces. The helix is covered by a sheath of flexible insulating material which may be covered by an armor which, in turn, may be covered by a protective layer of flexible insulating material.

HELICAL WAVEGUIDE

The present invention relates to improvements in helical waveguides with tight and closely adjacent coils, particularly suitable, by virtue of their flexibility, to join optically misaligned points.

The invention relates particularly to helical waveguides of the type described in co-pending application Ser. No. 139,436, filed May 3, 1971, in the names of Paolo Gazzana Priaroggia and Antonio Portinari and having a common assignee. The waveguides described therein are formed from insulated, helically wound conductive straps, wound on edge, and the adjacent turns are of the same cross-sectional shape. The so-formed helix is covered by at least a sheath of insulating material which may be covered by an armoring layer and a further sheath of insulating material. The major surfaces of the straps are flat or curved but are complementary so that continuous turns are in contact throughout such surfaces but are out of contact at their edge surfaces.

The deformation of a waveguide of this kind takes place along a neutral axis, which does not pass through the center of gravity of the waveguide, but which passes very near the outer edge of the coils of the helix. A waveguide of this type, although it is already very flexible with respect to the conventional ones, still maintains a certain undesirable rigidity in view of the purpose it is wished to obtain. In fact, the minimum admissible bending radius is still too great to permit the collection of the guide on easily transportable drums, either in the factory or in the field.

The invention according to the present application, aims at providing a helical waveguide, improved with respect to the waveguides of said co-pending application, which may be collected on drums of practical diameter, namely, on drums which can be normally transported in the factory or on the road.

A further aim of the present addition is that of obtaining a waveguide which, owing to its high flexibility, does not suffer a substantial deformation from circular to oval form when it is bent, so that its section is not subjected to deformations other than those permitted by usual tolerances and its possible deformation to oval form is merely of an elastic nature.

A still further aim of the present invention is that of providing an improved helical waveguide which may be subjected to considerable deformations before giving rise to spaces between the coils in the zones in which, when the guide is bent, the insulating sheath is stretched.

The main object of the present invention is an improved waveguide of the helical type similar to the waveguides described in said co-pending application, in that a sheath of thermoplastic material covers an inner helix whose coils are aligned and closely adjacent to one another and constituted by insulated conductors, in the form of straps and wound upright, but differing therefrom in that the helix is formed from a plurality of interleaved conductive straps, alternate turns being spaced from each other intermediate their free edges but being in contact with each other at least adjacent their contiguous free edges and preferably being of different cross-sectional shape or differently disposed when viewed from the same angle. Each strap is in contact with the adjacent strap, on one face, along at least

a first helical line and, on the other face, along at least a helical line having a diameter different from that of the first helical line, so as to create between the major surfaces of the turns a space permitting the free elastic deformation of the strap at each turn thereof.

Such object and other objects of the invention will be apparent from the following detailed description of presently preferred embodiments of the invention, which description should be considered in connection with the attached drawing in which:

FIG. 1 is a fragmentary, longitudinal section of an embodiment of the guide according to the invention, in which the straps are rectilinear in cross-section;

FIG. 2 is a similar view of an embodiment of the guide according to the invention, in which the straps are oppositely curvilinear in cross-section;

FIG. 3 is a similar view of a further embodiment of the guide according to the invention, in which the straps are curvilinear in cross-section but of different shape;

FIG. 4 is a similar view of an embodiment of the guide according to the invention, in which one strap is rectilinear in cross-section and the other has two rectilinear portions extending at an angle to each other; and

FIG. 5 is a similar view of a further embodiment of the guide according to the invention, in which one strap is rectilinear in cross-section and the other strap is curvilinear in cross-section.

In the drawings, like reference numerals indicate like parts.

The helical waveguide 10 represented in FIG. 1 comprises a cylindrical helix 11, preferably consisting of a strap of enamelled copper or aluminum, enclosed in a sheath 12 of thermoplastic material, as for instance polyethylene, which is covered by a protective armor 13 and by a second thermoplastic sheath 14. The armor 13 and the sheath 14 could however be omitted.

The cylindrical helix 11 comprises two straps 15 and 15'. Although a helix having a number of straps equal to, or multiple of, two is preferred, this does not exclude that waveguides with helices of $2n+1$ straps may be made according to the invention. The strap 15 is inclined with respect to strap 15'. Each turn of strap 15 touches, at its lower end, along a first helical line, the preceding turn of strap 15' and, at its upper end, along a second helical line, having therefore a diameter different from the first helical line, the subsequent turn of strap 15'.

In FIG. 2, the strap 15 is shaped in such a way as to have an arc of a circle curvature opposite with respect to that of the strap 15', and the bending radius of strap 15 is equal to the bending radius of strap 15'. In the embodiment of FIG. 2, the strap 15' is in contact, on one face, with the adjacent strap 15 along two helical lines, and on the other face, with the same strap 15 along a single helical line. In the illustrated embodiment, the centers of curvature of the straps are all aligned with one another, but obviously waveguides according to the invention could be obtained with a different alignment.

FIG. 3 illustrates helix obtained with straps 15 and 15' having different curvatures and arranged with the same orientation, namely with the centers of curvature directed in the same sense. Also here, the strap 15'

meets, on one face, the strap 15 along a single helical line, and on the other face again the same strap 15, but along two helical lines of different diameter. The same is true for the embodiments shown in FIGS. 4 and 5. In these embodiments, the strap 15, constituting one of the two starts, is rectilinear, i.e. has a pair of plane surfaces.

In the example of FIG. 4, the strap 15 has its cross-section constituted by two rectilinear lengths forming an obtuse angle with each other and connected by an arc. In FIG. 5, the strap 15 has its cross-section in the shape of an arc of a circle, and the strap 15' is rectilinear.

The waveguides may also be formed by straps having shapes other than those illustrated. For example, the helix could comprise alternating straps with equal or different polycentric curvatures.

All the embodiments have in common the fact that they comprise multiple helices and successive turns in contact with one another along one or more helical lines, so that spaces s , s' remain between the turns, which permit the free elastic deformation of the strap section in each turn. By means of this feature, when the illustrated waveguide is bent, in the compressed zone the straps move closer together in an elastic manner, while in the stretched zone the pitch is increased and the turns enlarge elastically, without detaching.

To facilitate this latter feature and to maintain it even in the event of unusual stretching of the sheath, it is preferable to sheath the cylindrical helix by extrusion. In this way, when the thermoplastic material (for instance, polyethylene) extruded in the extruder cools and shrinks, it preloads said turns, by virtue of its longitudinal shrinkage, in a considerable measure, but does not flatten them completely, so that in the finished article the straps are mounted in an axially preloaded or compressed condition. In other words, the straps, in condition of mechanical rest of the waveguide, namely, when the axis thereof is rectilinear, press elastically against each other. It is therefore possible to provide a waveguide whose elasticity is adjusted by the sheath and by the other protecting elements.

If desired, it is of course possible to preload the straps to the required extent with other conventional means, but such means are not preferred.

The strap of the helix can be made with the normally used materials, e.g. copper and aluminum, which will provide the elasticity necessary to obtain the flexibility requirements of the waveguide so produced. In particular, the straps having the shapes indicated in FIGS. 2 and 3 (circular section curvature) have a variable flexibility, since the pairs of straps become stiffer and stiffer as they flatten under load. This results in easier manufacture of the waveguide since narrow preloading tolerances are not to be taken into account during sheathing. Moreover, by virtue of the variable flexibility, the pitch differences along the guide axis, allowed

by the elasticity of the turns, tends to equalize, as a result of the equalization, which is better in the case of variable flexibility, of the deformation differences.

The improved flexibility of the whole waveguide also reduces the tendency of the waveguide to assume an oval cross-section when it is collected on a drum.

Although it has been indicated that several constructional forms can be adopted for the strap, which will assure a longitudinal elasticity for the package of turns, the straps having a circular section curvature, shown in FIG. 2, is the preferred one, since it assures, better than the other, ease of manufacture and the features of variable flexibility and of a constant pitch of the turns.

It is understood that the details of construction of the waveguide according to the invention may be varied as necessary, without departing from the principles of the invention.

What is claimed is:

1. A cylindrical waveguide comprising an inner wall formed by a plurality of interleaved insulated straps of conductive material wound in the shape of a helix, said straps being wound upright and disposed with their major surfaces extending transversely to the axis of said helix, each strap having a portion at one surface thereof in contact with an adjacent strap along at least one helical line and having a portion at the opposite surface thereof in contact with an adjacent strap along at least a second helical line having a diameter different from that of said one helical line and having portions of its major surfaces spaced from the major surfaces of the adjacent straps, thereby providing spaces between the major surfaces thereof, and a sheath of flexible insulating material surrounding said helix.

2. A waveguide as set forth in claim 1, wherein each strap has two portions at the opposite surface thereof in contact with an adjacent strap along two helical lines each having a diameter different from that of said one helical line.

3. A waveguide as set forth in claim 2, wherein at least one of said straps has, in cross-section, major surfaces which have the shape of arcs of concentric circles.

4. A waveguide as set forth in claim 3, wherein the strap adjacent said one strap is similarly shaped but oppositely disposed.

5. A waveguide as set forth in claim 2, wherein at least one of said straps has, in cross-section, two rectilinear portions extending at an obtuse angle with respect to each other and joined by an arcuate portion.

6. A waveguide as set forth in claim 1, wherein said straps are under compression axially of said waveguide when the axis of said waveguide is rectilinear.

7. A waveguide as set forth in claim 1, wherein alternate straps have different cross-sectional shapes.

8. A waveguide as set forth in claim 1, wherein alternate straps have the same cross-sectional shape but are differently disposed with respect to each other.
